UNITED STATES PATENT OFFICE.

LEWIS E. MORRISON, OF NEWARK, NEW JERSEY, ASSIGNOR TO HIMSELF AND
MATTHIAS PLUM, OF NEWARK, NEW JERSEY.

SHEET-FEEDING DEVICE.

1,108,211.

Specification of Letters Patent. Patented Aug. 25. 1914.

Application filed February 17, 1908. Serial No. 416,203.

To all whom it may concern:

Be it known that I, LEWIS E. MORRISON, a citizen of the United States of America, and a resident of Newark, Essex county, New Jersey, have invented certain new and useful improvements in Sheet-Feeding Devices, of which the following is a specification.

This invention relates to sheet feeding mechanisms for feeding paper to the platen 10 on a platen press, and the object of the invention is to provide a feed for handling sheets, envelopes or other matter in such a manner as to enable the press to be run at greater speed, than when fed by hand, and 15 also remove the dangers accompanying this latter method of feeding.

My feeding mechanism may, of course, be used on other machines than platen presses, but in this instance and in its preferred 20 form it is shown applied to a so called job press, and one of the new, novel and useful features of this invention is, that it may be put on an ordinary platen press in a few minutes, and by means of no other tool but 25 a wrench, and that no change or alteration of any kind is necessary in the construction of the press. Besides this obviously great advantage, my improved paper feed comprises a simple and convenient construction 30 containing the necessary elements for register and adaptability for operation at different speed and for handling different sizes of paper. Further, while in this instance it is shown as receiving the single sheet or envelope 35 from an operator, it will be seen that any suitable automatic separating mechanism may be used for presenting the single sheet to this feeding device. After the sheet has been printed between the form and the 40 platen, it may be removed by any suitable means.

Further objects and novel features of this invention will appear as the specification proceeds, setting forth the detailed construction, while reference is had to the accompanying drawings, in which—

Figure 1 is a side elevation of a job press equipped with my improved paper feed, with parts left out. Fig. 2 is a detail perspective view of the feed proper, Fig. 3 is a detail view of a tape positioning means and Fig. 4 is a detail view of a corner of the platen.

Referring now to Fig. 1 the reference nu-

meral 1 denotes the frame of an ordinary 55 and well known type of job press; 2 is the platen and 3 the form, which latter is carried by the form carrying member 4 pivoted at 5 and oscillated by means of connecting rods 6—only one of which is shown—and 60 gear 7 driven from pinion 8 on main shaft 9. The platen is of the oscillating type, and I do not need to go into detail about the operation or construction of a press of this character, which is so well known in the art, 65 further than to say, that the numeral 10 indicates the platen locking cam found on all presses of this kind for locking the platen while the printing is being done.

Referring now more particularly to Fig. 70 2, it will be seen that my feeding device is carried between and by two brackets 11, 11 which are fastened to the frame 1 by ordinary bolts 12, see Fig. 1. I pause here to point out that in Fig. 2 the platen is shown 75 in its retracted position ready to receive the paper, and that in this figure I have shown all the parts in dotted lines, which do not constitute a part of my invention. Above the brackets 11 I place a table 13 for receiving the pile of paper 14 which in this instance is supposed to be separated by hand and the single sheet 15 fed against a side registering guide 16 and then pushed onto the feed. The side guide is adjustable as 80 shown and may be used for feeding to either side. Pivoted in the brackets is the upper tape shaft 17 and journaled on this are the two swinging arms 18, 18, in the free ends of which the lower tape shaft 19 is 85 journaled; tapes 20 pass over and around these two shafts. The shaft 17 passes through the one bracket 11 and carries on the outside thereof a gear 21, which is driven from gear 7 on the press through the gears 90 22, 23 and 24, the latter of these meshing with gear 7. The gears 22, 23 and 24 are carried on studs on the bracket 11. The single sheet is pushed out over the shaft 17 and onto the tapes 20 and by these latter is carried down and dropped on the platen at the proper time. While passing on the tapes the sheet is side registered by the guides 25, 25, carried by rods 26, 26, which latter are adjustably fixed in posts 27, 27. The passage 105 of the sheet from the tapes to the platen is timed by means of the stops 28 adjustably fixed on rockshaft 29. The stops rest on the

shaft 19 and are held down by spring 30. At the proper moment, the stops are raised by the shaft 29 being rocked upwardly through the instrumentality of lever 31, link 32, bell crank 33 pivoted at 34, link 35 and lever 36, which latter is pivoted at 37 and carries a cam roll 38 coöperating with the platen locking cam 10. The rotary movement of the shaft 29 causes the stops 28 to be lifted out of the way of the sheet, which then passes out over the shaft 19 and drops on the platen, where its position is determined in the usual manner. The stripper fingers or platen grippers are not shown.

15 After the sheet is dropped on the platen, the latter moves down into printing position, consequently it is necessary to move the feed upward out of the way. This is accomplished in the following manner. Pivoted at 39 on the brackets 11 are two levers 40, one on either side, each of which coöperate with rollers 41, which latter are fastened to the platen as seen in Fig. 4. These two levers 40 each carry a cam roll 42, which 20 acts with the cams 43 mounted on arms 18. The levers 40 rest constantly on the rollers 41 in the platen, hence any movement of the latter affects the position of the levers and these in turn constantly support the feeding 25 device through the rollers 42 and cams 43.

As shown in Fig. 2 the platen is in position to receive the paper from the tapes. Immediately after the paper reaches the 30 stops 28 these latter are moved up by the cam roll 38 coacting with the low part of the platen locking cam 10, while the tapes, of course, rotate all the time. When the stops 28 are up the paper passes onto the platen, and the latter now moves downward 35 to printing position, and during this movement the rollers 41 lift the levers 40 up and they in turn lift the feed as seen in Fig. 1, where the platen is shown in its highest position with the feed high enough to let the platen pass under it. The further movement of the platen simply causes the feed again to be lowered. After the printing is 40 done, the platen again moves up, lifts the feed out of way, passes under it and is ready 45 to receive the next sheet, which in the meantime has been placed on the tapes by the operator or a separating mechanism. Lever 50 31 is joined to the link 32 by a pin and slot connection, so that when the feed is swung up, the spring 30 is free to act to close the stops on shaft 19 in time to arrest the passage of the next sheet on the tapes.

The above is thought to clearly set forth 55 the construction and operation of my invention. It will be noticed that the feeding mechanism is one unit as shown in full lines in Fig. 2, and that this unit is complete and may be readily placed on or removed from the press. The rollers 41 need in most instances never be removed from the platen.

Further, the mechanism may readily be made to fit any width of the press and can as readily be adjusted to suit any size sheet, as the stops and side guides are adjustable sideways. The brackets are joined by suitable rods or bars 44 and one other rod 45 is provided, which carry clips 46 for adjusting the position of the tapes. Only one of the clips is shown in Fig. 2 for the sake of clearness.

75 Fig. 3 shows a detail view of a clip, which is made of springy metal and is provided with spring positions 47 and 48 for gripping the rod 45 and has depending wings 49 for guiding the tape. By sliding these 80 clips on the bar 45 the tapes are prevented from moving sideways after once being positioned.

85 Another feature which should be noted, is, that the feed is operated by parts which belong to the press proper and that no connections or extra parts are added.

90 The construction may of course vary considerably within the scope of the claims and I do not wish to be limited to the precise form shown.

I claim.

1. A sheet feeding device for platen presses having a movable platen and a cam for locking said platen in printing position 95 comprising a sheet conveying means, mechanism for arresting the movement of the sheet at a predetermined point and at predetermined intervals, means for operating said mechanism by the said cam, means for 100 driving said conveying means constantly in one direction, and means for oscillating said device by the movement of said platen.

2. A sheet feeding device for platen presses, having a movable platen comprising 105 a frame, a feed table, a sheet conveying mechanism pivoted on said frame for conveying a sheet from the said feed table to the platen, two levers pivoted on the frame, and means for oscillating the said 110 levers to move the said conveying mechanism up when the said platen moves into printing position.

3. A sheet feeding mechanism for platen presses comprising means for conveying and 115 registering a sheet, means for timing the movement of said sheet at predetermined intervals before the same reaches the position to be printed, means for driving said conveying means, means for operating the said timing means, a frame for supporting all of the above mentioned mechanisms and combining the same into a machine unit adapted to be operated by the combined actions of the platen, the driving gear and the platen 120 locking cam of the said press.

4. A sheet feeding mechanism for platen presses, having a movable platen, comprising a frame, a table on said frame for receiving a pile of sheets, an adjustable side 130

- guide on said table, sheet conveying means pivoted on said frame, adjustable side registering guides carried by the said conveying means, adjustable means for stopping the movement of the sheet at predetermined intervals, all of the aforesaid means being supported by the said frame and means for automatically operating the said feeding mechanism by the action of the said press.
- 5 10. 5. A sheet feeding device for platen presses having a movable platen comprising brackets detachably mounted on the frame of the said press, sheet conveying means pivoted in the said brackets and overhanging the said platen, driving means carried by one of said brackets for driving the said conveying means constantly in one direction and means for oscillating the said conveying means by the movements of the said platen.
- 15 20. 6. A sheet feeding mechanism for platen presses having a movable platen comprising side brackets adapted to be attached to the side frames of the press, sheet conveying means and driving means for the same carried by the said brackets, movable members pivoted in the latter and interposed between the said conveying means and the said platen and actuated by the latter to oscillate the said conveying means.
- 25 30. 7. A sheet feeding mechanism for platen presses having a movable platen comprising side brackets, oscillating members supported by the latter and adapted to coöperate with the said platen, sheet conveying means pivoted in the said brackets and resting on the said oscillating members and means for driving the said conveying means.
- 35 40. 8. A sheet feeding mechanism for platen presses having a movable platen comprising an upper and lower tape shaft, tapes on the same, means for constantly driving the said tapes and means for oscillating the said feeding mechanism by the movements of the said platen.
- 45 50. 9. The combination of a movable platen, sheet conveying means pivoted on a fixed pivot adjacent the same and projecting into the path of the said platen and means for moving the said sheet conveying means out of the path of the said platen and into the path of the said platen by the movements of the same, said last mentioned means comprising pivoted members having frictional contact with the said platen and the said conveying means.
- 55 60. 10. A sheet feeding attachment for platen presses contained in a separate machine unit and comprising sheet conveying means, timing means, side registering means, a frame-work for supporting all of the said means and movable members pivoted on the said frame work and forming a support for the one end of the said sheet conveying means.
- 65 65. 11. The combination of a movable platen, a platen locking cam, sheet conveying tapes, means coacting with the said platen for oscillating the said tapes, timing means and means coacting with the said locking cam for operating the said timing means.
- 70 12. The combination of a movable platen, a platen locking cam, sheet conveying means, registering means, timing means, means coacting with the said platen for oscillating all of the aforesaid means and means coacting with the said locking cam for periodically operating the said timing means.
- 75 80. 13. The combination of a press having a movable platen, a platen locking cam and a driving mechanism, a sheet feeding device comprising conveying means, pivoted supporting arms for the same, movable members interposed between the said arms and the said platen and coacting with the latter for oscillating said arms, sheet stops on said arms, operating connections coacting with the said cam for operating the said sheet stops and means adapted to coact with the said driving mechanism for driving the said conveying means.
- 85 90. 14. A sheet feeding attachment for printing presses comprising side frames, conveying means pivoted on said frames, levers also pivoted on said frames, cam rolls on said levers and cams secured to the said conveying means and resting by gravity on the said cam rolls.
- 95 100. 15. A sheet feeding attachment for printing presses comprising a pair of pivoted arms, tape shafts carried by the same, tapes on said shafts, side registering means supported on said arms, movable supports for the arms and a common frame work for all of the aforesaid elements and separate from the frame of the said press.
- 105 110. 16. A sheet feeding attachment for printing presses comprising conveying means, means for oscillating the same vertically in synchronism with the operations of the press, sheet stops movable with the said conveying means and connections for positively moving the said stops out of the path of the sheet when the said conveying means are in their lower position.
- 115 120. 17. A sheet feeding attachment for printing presses comprising conveying means, means for oscillating the same vertically in synchronism with the operations of the press, sheet stops movable with the said conveying means, connections for positively moving the said stops out of the path of the sheet when the said conveying means are in their lower-most position and a spring for moving the said stops into the path of the sheet when the said conveying means are in their upper-most position.
- 125 130. 18. A sheet feeding attachment for printing presses comprising sheet conveying means, supporting means therefor, movable members pivoted on the latter for oscillating the said conveying means, cam rolls on said

- members, cams on the said conveying means and resting upon the said cam rolls by gravity.
19. A sheet feeding attachment for printing presses comprising a pivoted tape table, sheet stops carried by the same, means for normally keeping said stops in their lower-most position on said table, devices for oscillating the latter and connections for raising the said sheet stops when the tape table is in its lower position and for permitting the said means to operate when the tape table is in its upper position.
20. The combination of a platen, a pair of levers resting by gravity thereon, a tape table resting by gravity on said levers and comprising a plurality of sheets conveying tapes and supporting means therefor and means for operating said tapes.
21. The combination of a movable platen, sheet conveying means pivoted above and in front of said platen and projecting into the path thereof, means interposed between the said conveying means and the said platen and in frictional contact with both of the said elements for oscillating the said sheet conveying means by the movements of the said platen.
22. The combination of a movable platen, sheet conveying means pivoted to operate as a separate unit, means interposed between the said conveying means and the said platen and in frictional contact with both of the said elements for oscillating the said conveying means by the movements of the platen.
23. The combination of a movable platen, sheet conveying means pivoted to operate as a separate unit, sheet timing devices carried by the said unit, means interposed between the said unit and the said platen and in frictional contact with both of the aforesaid elements for operating the said unit by the movements of the platen and means for operating the said sheet timing devices.
24. The combination of a movable platen, a sheet conveying mechanism adapted to be operated as a machine unit sheet timing devices secured to the same, movable members interposed between the said mechanism and the platen and in frictional contact with both of the said elements for operating the said mechanism by the movements of the said platen and means for operating the said timing devices independently of the operation of the said conveying mechanism.
25. A sheet feeding attachment for printing presses having a movable platen and platen locking means said attachment consisting of a self contained structure adapted to be attached to the said press and comprising a conveying tape table, means for operating the latter by the movements of the said platen, sheet timing means and connections for operating the latter from the said platen locking means.
26. A sheet feeding mechanism for printing presses having a movable platen comprising an upper and a lower tape shaft, tapes on said shafts, timing means in periodical contact with the said lower shaft, means for oscillating said tapes and said timing means together and in synchronism with the movements of the press and other means for operating said timing means independently of the said oscillations.
27. A sheet feeding mechanism for printing presses having a movable platen and a platen locking device, said feeding mechanism comprising sheet conveying means, timing means in periodical contact with said conveying means, means for oscillating both said conveying and said timing means by the movement of the said platen and other means for periodically operating the said timing means by the said platen locking device.
28. A sheet feeding attachment comprising side supports, a shaft journaled therein, arms pivoted on the said shaft, conveying means carried by the said arms, movable members secured to the said side supports and coöperating means carried by the said movable members and the said arms for supporting the latter by gravity on said members.
29. A sheet feeding attachment comprising supports, a pair of arms pivoted thereon, sheet conveying means carried by said arms, movable members pivoted to the supports, cam rolls on said members, cams fixed to the said arms and adapted to rest on said cam rolls for supporting the said arms and for oscillating the same in unison with the movements of the said members.
30. A sheet feeding attachment comprising supports, sheet conveying means pivoted thereon, side register means secured to the said conveying means, timing devices pivoted on the latter and adapted to coöperate therewith, operating connections for the said timing means pivoted on the said supports and movable members also pivoted on said supports and in frictional contact with the said conveying means for the support of the latter.

Signed at New York, N. Y. this 10 day of Feb. 1908.
